United States Patent Office

Des. 190,222
Patented May 2, 1961

190,222

OVERSHOE OR THE LIKE

Stedman C. Pool, Essex, Conn., assignor to Essex Master Mold Co., Inc., Essex, Conn., a corporation of Connecticut

Filed Feb. 2, 1960, Ser. No. 59,239

Term of patent 14 years

(Cl. D7—7)

Fig. 1.

Fig. 2.

Fig. 3.

Fig. 4.

Fig. 5.

Fig. 6.

Fig. 1 is a side elevational view of an overshoe embodying my new design;

Fig. 2 is an elevational view, looking from the side opposite that shown in Fig. 1;

Fig. 3 is a rear elevational view of the overshoe;

Fig. 4 is a perspective view of the rear lower portion of the overshoe;

Fig. 5 is a perspective view of the rear portion of the overshoe, looking toward the bottom thereof; and

Fig. 6 is a front perspective view of the overshoe.

I claim:

The ornamental design for an overshoe or the like, as shown.
